Primary Examiner — Lauren D McVey*Assistant Examiner* — Sarah L Smith*(74) Attorney, Agent, or Firm* — JCIPRNET(57) **CLAIM**

The ornamental design for a projection lamp, as shown and described.

DESCRIPTION

FIG. 1 is a perspective view of a projection lamp showing my new design;

FIG. 2 is a front view of FIG. 1;

FIG. 3 is a rear view of FIG. 1;

FIG. 4 is a left side view of FIG. 1;

FIG. 5 is a right side view of FIG. 1;

FIG. 6 is a top view of FIGS. 1; and,

FIG. 7 is a bottom view of FIG. 1.

The broken line portions of the projection lamp in FIGS. 1–7 represent portions of the projection lamp and form no part of the claimed design.

1 Claim, 7 Drawing Sheets(56)
